OP D 19,274

DESIGN.

C. E. HAVILAND.
DISH.

No. 19,274.

Patented Aug. 20, 1889.

UNITED STATES PATENT OFFICE.

CHARLES ED. HAVILAND, OF LIMOGES, FRANCE.

DESIGN FOR A DISH.

SPECIFICATION forming part of Design No. 19,274, dated August 20, 1889.

Application filed January 5, 1889. Serial No. 295,570. Term of patent 14 years.

To all whom it may concern:

Be it known that I, CHARLES EDWARD HAVILAND, a citizen of the United States, residing at Limoges, Republic of France, have 5 invented and produced a certain new and original Design for Dishes, fully described and represented in the following specification and the accompanying illustration, forming a part of the same.

10 In the accompanying illustration, Figure 1 is an end view of a covered dish embodying the design, and Fig. 2 a perspective view of the same.

15 The following are the leading features of the design: The sides *a* and ends *b* of the dish-body are plain and are curved outward slightly, so as to give a slightly oval or rounded form to the upper edge of the body. The corners of the body are more rounded and are corrugated 20 vertically, as shown at 2, so as to give the upper edge of the body a scalloped form at the corners. The corrugations at the corners of the body vanish as they approach the base of the body.

25 The cover is somewhat dome-shaped, and in outline corresponds substantially to the outline of the top of the body, its sides *c* and ends *d* being plain and slightly curved outward and its corners rounded, so as to give a 30 somewhat oval or rounded form to the cover. The corners of the cover are also scalloped to correspond to the scalloped outline of the corners of the body. The corners of the cover are also corrugated, as shown at 4, the corrugations converging toward and vanishing as 35 they approach the center of the cover. The corrugations upon the cover correspond with the scallops upon its corners and are all convex.

The cover is provided with a handle *f* representing a gnarled and twisted branch of conventional form, the ends of which unite with the cover and extend along the top of the cover, with some of the twigs and leaves more or less in relief, as indicated at 6. 40

The dish-body is also provided with handles *g* of similar form, the ends of which unite with the body, while the central portions curve outward and upward. 45

What I claim is—

1. The design for a covered dish, substantially as herein shown and described, the same comprising the body and cover. 50

2. In a design for a dish, the design for the cover, substantially as herein shown and described. 55

3. In a design for a dish, the design for the body, substantially as herein shown and described.

In testimony whereof I have hereunto set 60 my hand in the presence of two subscribing witnesses.

CHARLES ED. HAVILAND. [L. S.]
